UNITED STATES PATENT OFFICE.

CARL S. KLUMPP, OF BROOKLYN, NEW YORK.

DOOR-CONTROL SYSTEM.

Application filed January 11, 1922. Serial No. 528,473.

This invention relates to a safety remote control and locking system for doors or gates, particularly those on rapid transit electric cars or other public utility vehicles, and has for its object: first, the provision of a locking system controlled and operated independently of the door operating and control system whereby the doors when closed are locked in that position and are secured against accidental opening due to the inadvertent manipulation of the operator's door opening controls or by any failure or derangement of the electrical or the mechanical devices of the door opening circuits or mechanisms and preferably having indicating means operating in conjunction with the locking system to show the locked or unlocked condition of the doors; second, the provision of a simple and effective door locking device which automatically operates upon closure of the door to lock it in its closed position and which must be positively actuated before it is possible to open the door.

To this end, locking devices are affixed adjacent to one or more doors and are provided with associate devices for selective actuation thereof and for operating the indicating means. The indicating means operated by these devices may be located in a motorman's or engineer's cab or at the guard's position and at such other positions on the car, train or vehicle as will best serve to indicate to those in charge of the doors the locked or unlocked position of any or all car doors. One embodiment of the locking device which has been found to be particularly effective and which is readily adapted for use in conjunction with the electro-pneumatic door opening and closing controls now in general use comprises a pivoted latch or bolt or other member positively retained, which is adapted to lock and hold the door in its closed position until a retaining latch is released. Other forms of the locking device may be employed which may omit the retaining latch or have other modifications which are suitable for the place or position in which they are used.

The control system for the locking device operates the locking device independently of the door opening and closing system and requires the operator to manipulate the locking control before the door opening control or to manipulate the combined control according to a predetermined selective pro-

gram. In order that the locked or unlocked condition of the doors may be indicated to the operator or others, a system of electric signals may be employed which are controlled by means associated with the locks. In this way, the operator or motorman or both are informed whether or not the door or doors are actually locked or unlocked rather than merely closed or open.

In accordance with the invention, the door operating mechanism and the locking mechanism may be either electrically, mechanically or pneumatically controlled or operated by independent systems, or one may be controlled by one form of these energies and operated by another and vice versa or any other independent actuating means or combination of actuating means may be employed.

Heretofore, it has been the practice to utilize one control to both release the locking device and open the doors of a car or the like. In some cases, movement of the opening means effected the release of the locking means. The locking of doors has also been obtained by moving the door opening lever past dead center. All of these methods have been found to be exceedingly unsatisfactory in that they provide no positive system of locking and indicating the locked condition, the control and operation of which was independent of the door control and operating system. It was quite possible in these systems for passengers to intentionally or accidentally manipulate the single control and cause the door or doors to open. Moreover, in some systems passengers could actually force the door open against the air pressure holding it or trip the small latch securing it and thus gain entrance after the doors were closed by the operator and when the car was ready to start.

It is often the case that doors become stuck in the closed position so that the door opening device does not exert sufficient force to open the door, but, however, exerts a constant force tending to open the door. When the train is in motion the jar of the car or the accidental jar by a passenger may so free the door that it will slide open with attendant danger to passengers.

Leaky valves or pistons, failure by improper functioning of valves, derangement of electric control apparatus and circuits introducing unintended energy, broken or loose parts of door control and operating

devices and the like are conducive to the accidental opening of doors. It is the intent of this invention to provide independent means safe-guarding the opening of doors 5 irrespective of failures or the improper functioning of the door operating mechanisms and devices.

A more complete understanding of the 10 operation of the safety control and locking system, wherein the door opening and closing controls are operated independently of the locking means and wherein the indication is automatically given of the locked or unlocked condition of the doors, may be had 15 by reference to the accompanying drawings and from the following description of the preferred embodiment of the invention. In these drawings:

Fig. 1 is a view of one form of the device 20 as applied to a door and shows schematically the arrangement and relation of the door opening device, the locking means and the indicating means.

Fig. 2 is a sectional view of a preferred 25 form of locking mechanism.

Fig. 3 is a view showing an arrangement of electric switches for the indicating means.

Fig. 4 illustrates a wiring diagram of the 30 lock release mechanism, the guard's indicating lights and the motorman's indicating lights and Fig. 5 shows the positions of the indicator light switch and circuits.

Referring now to Fig. 1, a sliding car door 4 is shown with its pneumatically operated 35 actuating cylinder 5, the operation of which is controlled by the electrically operated valve 6. The piston within the cylinder 5 operates the door 4 by means of the arm 2 and associate devices. The apparatus enclosed by the dotted line 7 comprises the locking and indicating device proper. The arm 8 is adapted to catch and hold the door as shown and a retaining lever 9 is adapted to be operated by the solenoid 10. 40 The cam block 11, bearing switch contacts, is arranged at one end of the lever 9. The indicating lights, for example 12 and 13, are controlled by these switch contacts and are adapted to indicate to the guard or other 45 train-man, the locked or unlocked condition of the doors, but additional lights and circuits may be provided for indications at other places if desired. The switch 15 controls the opening and closing of the door 50 and the switch 14, preferably a push button, controls the unlocking of the door. These two controls are placed so as to be conveniently operated simultaneously or selectively with one hand and the indicating lights are 55 placed so to be easily visible to the guard. The energy for the electrical circuits may be supplied from any convenient source.

The operation of the system shown in Fig. 60 1 is as follows: In order to open the door 4, which is shown in the closed position re-

tained by the locking arm 8, the guard first operates the lock control switch 14. This energizes the solenoid 10 which actuates the lever 9 withdrawing it from its retaining position behind the arm 8 and at the same 70 time changing the cam contacts to indicate the unlocked condition of the door. When the lever 9 is withdrawn the latch 8 is held in position only by the spring 16. The guard now operates his door opening control 75 15 and the door in sliding open, pushes the arm 8 out of its path. If a push button control is used at 14, the circuit 10 will be broken automatically as soon as the push button is released and to close and lock the door, 80 only the closing control switch 15 is manipulated. When the door is closed, the spring 16 automatically forces the arm 8 into position behind the door 4 and draws the retaining lever 9 into place behind the locking arm 8. Should the door opening control switch be operated without previously operating the lock release switch, the door would be prevented from opening as it could not push the arm 8 out of its path, due to the interlocking action of the arm 8 with the retaining lever 9. A series circuit 18 includes a lamp 12, preferably green, and the contacts 17 on the cam 11. If only one lock is used, the circuit will be completed through conductors 53 and 54; ordinarily, however, more than one door is to be locked, and the conductors 53 and 54 lead to the locks on the other doors and include contacts such as 17 on each lock. When all doors are 100 closed and locked all the contacts such as 17 will be closed by a wiper 55, the series circuit 18 will be complete and the lamps 12 will be lighted. It is to be noted that the circuit 18 is included in each of the door 105 indicating systems and requires that all doors be locked before the circuit is complete. A multiple circuit 40 includes a lamp 13, preferably red, and the contacts 19 on the cam 11. A similar circuit is provided for each lock used and it is preferable for simplicity that all these multiple circuits include the same red lamp 13. Should any door or doors be open the lamp 13, preferably red, will be lighted due to its circuit 110 being completed at 19.

The locking and switching device is best understood by reference to Fig. 2. The metal box or frame 7 supports and contains the entire device and is provided with lugs or holes 20 for attachment to the frame or other portion of the car. The box structure is divided by a diagonal web 21 for reinforcement against great strain brought about by an attempt to open a locked door. The arm 8, suitably shaped, is mounted within the box 7 on a pivot 22 and extends through an opening 23 in the box into the path of the door which it is desired to lock. A roller 24 is journaled at the end of the arm 120 125 130

8 to insure easy operation when this arm is in contact with the door. In a part of this arm 8, is formed a notch 25 which serves to engage the end of the retaining lever 9, which is suitably shaped to enter the notch and prevent the retaining lever from being forced out of engagement with the arm 8 should the door tend to open while locked. A projection 26 is provided on the arm 8 to 10 which a tension spring 16 is attached to force the locking arm 8 into position when the door is closed. The other end of this spring 16 is conveniently attached to the lever 9 and thus tends to keep this lever 15 in position behind the notch 25 on the locking arm. The lever 9 continues past its pivot point 27 and carries on its other extremity the insulated cam block 11, the surface of which is a cylinder the axis of curvature of which is at the pivot axis 27. This shape insures a constant pressure of the brushes 28 against their contacts 31 on block 11. The brushes 28 are mounted on an insulating block 34 and are provided with 20 means of connection to outside circuits. The plunger 35 is pivotally connected to the lever 9, and is adapted to be drawn within the solenoid 10 when it is energized by the operation of the locking control switch. 25 The bushing 36 serves as a convenient means for introducing all electric circuit wires. Outside of the box a pin 37 is attached by a chain or other means and is adapted to be inserted in the hole 38 drilled in the 30 arm 8 just outside the containing box 7. The insertion of this pin renders the movement of the lock impossible by any means and serves to permanently lock improperly operating doors.

35 The proposed arrangement of brushes and contacts for the indicating device is shown in Fig. 3. Brushes 28, 29 and 30 are provided and metal contacts 31, 32 and 33 are mounted on the insulating block 11 carried by the lever 9, as shown in Fig. 2. The 40 brushes are mounted on an insulating block 34 and are provided with circuit connections.

45 The operation of this device is very simple since there are but two moving parts, the arm 8 and the lever 9. When the door is closed the spring 16 forces the arm 8 behind the door and, if the solenoid is not energized, pulls the lever 9 into position behind the 50 retaining slot 25, thus locking the door. To open the door the solenoid 10 is energized and draws the plunger 35 down thereby lifting the end of the lever 9 from behind the arm 8 and enabling the door, when actuated, to push the arm 8 out of its path. When the door is locked, the lever 9 is in such a position that the contact 31 will 55 connect the wipers 28 and complete any circuit in which they are connected, such as the indicating circuit 43 shown in Fig. 4.

At the same time the contact 32 will complete a circuit (which may be circuit 18 of Fig. 4) through the wipers 29. When the door is unlocked, the contacts 31 and 32, are removed from their respective wipers and the circuits controlled thereby are opened. Simultaneously, however, the contact 33 engages the wipers 30 and completes any circuit in which they are included, as, for example, the circuit 40 of Fig. 4.

A six door car installation of a locking and indicating system with five different circuits is diagrammatically shown in Fig. 4. These circuits are conveniently referred to as the red light or danger circuit 40, the green light or clear circuit 18, the yellow light or caution circuit 42, the motorman's circuit 43 and the solenoid circuits 44. For convenience all circuits are grounded and are energized by the same source. The contact cams 11, which are operated by the lock releasing solenoids 10, are shown in the locked position. It is preferred that the lamps 12, 13 and 45 shall be green, red and yellow respectively. The motorman's lamp 46 may be of any color. The motorman's circuit 43 is carried through the whole train by the jumper terminals 47, making his proceed indication dependent upon the locking of all the doors of the train as will be hereinafter described. Four lock control switches 14 are provided for each end of the car and each guard may control two center doors as well as two end doors. In order to simplify the drawing, the door opening system has been omitted, but as a typical installation at one door showing both the door operating means and the door locking means has been illustrated in Fig. 1 and inasmuch as the same reference characters are used throughout for similar parts, it is felt that the operation of the complete system will be clear even though the door opening system is omitted. Although the lock mechanism is represented diagrammatically, it is felt that it will be clearly understood by reference to the preceding figures and description.

Considering now the end A of the car, when the four doors controllable from that end are closed and locked, the green light 115 series circuit 18 is closed by contacts 32 and the lamp 12 at that end will be lighted. This circuit 18 is energized from the positive terminal 56, and includes in turn the contacts 32 on each of the doors B, C, D 120 and E and the green lamps 12 and is completed through the switch 52 to ground as shown, this being the negative terminal of the energy source. As soon as any one of the doors is unlocked, the series circuit 18 125 is broken and the lamps 12 go out at the end of the car at which the door is unlocked. In case the center door is unlocked the green lights 12 go out at both ends of the car as 130 the energy for the green lights at both ends

- of the car includes the two center door contacts 32. In order to indicate the unlocked condition of any door, a multiple circuit 40 is provided, which includes two feeders 57 and 59, the feeder 57 having a tap for each lock except G and E and being connected to the ground through the red lamps 13, and the feeder 59 having a tap for each of the locks and including the positive terminal of the energy source. A lead 60 is brought to the locks G and E from the contact 61 on switch 52. The function of switches 52 will be explained in more particularity hereinafter, but for the present it is sufficient to say that in one position the contact 61 is connected to contact 62, thereby forming a complete circuit through the red lamp 13 to the ground. It will be seen that by this arrangement if the two taps 40 at any lock are connected together, the circuit will be completed through the red lamps 13. The contact 33 on the cam block 11 is provided to complete this circuit whenever its door is unlocked.
- 25 In order to provide an indication for the motorman of the locked condition of all the doors, a separate circuit 43, which passes in turn through all the locks on all the doors, is provided. Assuming that A is the head end of the train and the switch 48 at that end is thrown so as to close contacts 51, the circuit 43 through the motorman's signal 46 will be completed through the lead 58, which includes in order the contacts 31 in doors E, D, B, C, F and G. The switch 48 at the other end of the car should be thrown so as to connect the terminals 49, which continues the circuit through the jumper 47, which is adapted to be connected to the next car, which is similarly arranged. The circuit then passes through all the other locks in a similar manner and at the rear end of the train the circuit is completed to the positive terminal of the energy source preferably through switch 50, which is closed only when the rear signal lamp is mounted. When all of the doors of the train are closed and locked, the circuit 43 will be completed by means of the contacts 51 on the cam blocks 11, and the motorman's signal light 46 will be lighted. Should any door become unlocked, the circuit will be broken and the light 46 will be extinguished. The switch 48 is provided to enable the car to be used in any position in the train and to enable the motorman to operate his door without open-circuiting his indicating lamp. When the contacts 49 of this switch are connected the car may be used as a rear car or in an intermediate position as the lead 58 is disconnected from the signal 46 and is connected to the lamp switch 50 and jumper terminals 47. When used as a rear car, the rear signal lamps must be mounted in order to close the switch 50 which controls the energy connections for the motorman's signal circuit. Thus a positive indication is given to the motorman that the rear signal lamps are mounted. When used as an intermediate car, current is received and the motorman's circuit established through the jumper terminal 47. When the switch 48 is thrown so as to connect the terminals 51, the lights 46 are in circuit and this end of the car may be used as the head end of the train.
- 30 The yellow light circuit 42 is provided so that the motorman may operate his door without confusing the guard on that car by lighting the red light. To this end the switch 52 which has been previously referred to is provided which has two positions. In the positions (X and Y) shown in Figure 5 the contacts 61 and 63 are connected to contacts 62 and 64 respectively, thereby closing in position X the red light circuit 40 and the green light circuit 18 at the A end of the car, and disconnecting the yellow light circuit 42. In the other position the red and green light circuits 40 and 18 through the motorman's door E and the adjacent door D are open and the yellow light circuit 42 is closed. In operation the switch 52, which is on the front end of the train, is thrown so that the yellow light circuit is closed and all other switches 52 are thrown so as to connect the red and green light circuits. The unlocking of the motorman's door will now complete the yellow light circuit 42 instead of the red light circuit 40 by means of the contact 33 and will give a yellow light indication to the guard, who under these conditions is at the other end of the car. Should any other door be unlocked, the red light circuit 40 will be closed as usual and the guard may have a red light indication and a yellow light indication. When all doors are locked except the motorman's, the guard will have a yellow light indication and a green light indication, which for the head car will signify the locked condition of all doors and will enable him to signal to proceed.
- 35 From the foregoing it will be understood that this system of door or gate control provides a simple and efficient means of eliminating the ever-increasing danger due to accidental door opening. The system requires two separate yet simple operations to effect the opening of the door and also provides an indicating system by which the guard can tell at a glance whether or not all doors are locked in the closed position. It is not intended, however, that the foregoing description of a specific embodiment is to at all limit the spirit or scope of this invention as it is apparent that due to the various types of cars and different conditions to be met, the arrangement of

the door locking system and the construction of the various parts may be modified accordingly.

I claim:

- 6 1. In a car door control, a locking system for vehicle doors, and in combination with pneumatically operated door operating devices and electrically controlled door locking devices, means for operating the locking devices independently of the door operating devices, and means for indicating the locked and unlocked condition of the doors.
- 10 2. In a remotely controlled safety operating and locking system for pneumatically operated doors on vehicles, door operating means, and an electric control therefor, independent lock operating means, an independent control system therefor, and means operated in conjunction with said locking means for indicating the locked and unlocked condition of the doors, said indicating means being located at the motorman's station of the vehicle.
- 15 3. In a remotely controlled safety operating and locking system for car doors, the combination with a plurality of doors and

locks therefor, to secure said doors in closed position, of pneumatically operated means for opening and closing said doors, electrically operated means for independently actuating the locks into position for unlocking the doors, and means independently controlled for indicating the relative positions of the doors.

30 35 4. In a remotely controlled safety operating and locking system for doors and the like, in combination with a plurality of doors, means for operating said doors, locks adapted to lock said doors in the closed position, means for operating and controlling said locks independently of the door opening means, series electric circuits adapted to be closed by the locking of all of said locks and opened by the unlocking 40 of one of said locks, multiple electric circuits for each door each adapted to be opened when its lock is locked and closed when its lock is unlocked, and means included in these electric circuits to indicate the 45 locked or unlocked condition of the doors.

40 45 50 In testimony whereof I affix my signature.

CARL S. KLUMPP.
